COMBINED SPOTLIGHT AND REAR VIEW MIRROR FOR VEHICLES

David M. Morgenstern, Euclid, Ohio, assignor to Nelmor
Manufacturing Corporation, Euclid, Ohio, a corpora-
tion of Ohio

Filed Mar. 22, 1960, Ser. No. 59,829

Term of patent 14 years

(Cl. D48—32)

Figure 1 is a side elevation of a combined spotlight and rear view mirror for vehicles showing my new design;

Figure 2 is a perspective view thereof looking toward the rear view mirror end; and

Figure 3 is a perspective view looking toward the spotlight end of the unit.

I claim:

The ornamental design for a combined spotlight and rear view mirror for vehicles, as shown.
